Primary Examiner — Sheryl Lane(74) *Attorney, Agent, or Firm* — Burr & Forman LLP;
Douglas L. Lineberry(57) **CLAIM**

The ornamental design for a vegetative sheath, as shown and described.

DESCRIPTION

FIG. 1 is a front perspective view of the vegetative sheath; FIG. 2 is a front elevated view of the vegetative sheath; FIG. 3 is a back elevated view of the vegetative sheath; FIG. 4 is a left elevated view of the vegetative sheath; FIG. 5 is a right elevated view of the vegetative sheath; FIG. 6 is a top plan view of the vegetative sheath; FIG. 7 is a bottom plan view of the vegetative sheath; FIG. 8 is a left perspective of the vegetative sheath in an open position; and FIG. 9 is a perspective view that shows two vegetative sheaths joined to one another in a side by side configuration. FIG. 10 is a perspective view that shows two vegetative sheaths joined in an end to end configuration; and, FIG. 11 is a plan view that shows the vegetative sheath in a flat configuration. The broken lines represent environment and form no part of the claimed design.

1 Claim, 7 Drawing Sheets(56)
